(57) **CLAIM**

The ornamental design for an orthopedic implant sizing device, as shown and described.

DESCRIPTION

FIG. 1 is a perspective view illustrating the orthopedic implant sizing device showing our new design; FIG. 2 is a front elevational view thereof; FIG. 3 is a rear elevational view thereof; FIG. 4 is a left side elevational view thereof; FIG. 5 is a right side elevational view thereof; FIG. 6 is a top plan view thereof; and, FIG. 7 is a bottom plan view thereof.

The broken lines shown in FIGS. 1-7 represent additional portions of the orthopedic implant sizing device that form no part of the claimed design.
